(57) **CLAIM**

(21) Appl. No.: **29/628,000**

The ornamental design for a harness case for electronic device, as shown and described.

(22) Filed: **Nov. 30, 2017**

Related U.S. Application Data

(63) Continuation of application No. 29/567,082, filed on
Jun. 6, 2016, now Pat. No. Des. 804,183.

DESCRIPTION

(51) **LOC (11) Cl.** **03-01**

FIG. 1 is a front perspective view of a harness case for
electronic device without showing the case.

(52) **U.S. Cl.**

FIG. 2 is a rear perspective view thereof.

USPC **D3/327; D3/318**

FIG. 3 is a front view thereof.

(58) **Field of Classification Search**

FIG. 4 is a right side view thereof, the left side view being
a mirror image thereof.

USPC **D3/318, 327**

FIG. 5 is a bottom view thereof, the top view being a mirror
image thereof.

CPC **A45C 11/182; A45C 11/18; A45C 3/04**

FIG. 6 is a rear view thereof.

See application file for complete search history.

FIG. 7 is a rear view of the harness case for electronic
device; and,

FIG. 8 is a front view thereof.

The broken lines depict environmental subject matter and
form no part of the claimed design.
